Eastman & McCartney LLP(57) **CLAIM**

The ornamental design for a mobile device charger bag charm, as shown and described.

DESCRIPTION

FIG. 1 is a bottom front perspective view of a mobile device charger bag charm;

FIG. 2 is a front elevation view thereof;

FIG. 3 is a rear elevation view thereof;

FIG. 4 is a bottom elevation view thereof;

FIG. 5 is a top elevation view thereof;

FIG. 6 is a left elevation view thereof;

FIG. 7 is a right elevation view thereof; and,

FIG. 8 is a bottom rear perspective view thereof shown in an environment of use.

The broken lines shown in the drawings illustrate portions of the mobile device charger bag charm that form no part of the claimed design.
